UNITED STATES PATENT OFFICE.

PATRICK H. REARDON, OF SAN FRANCISCO, CALIFORNIA.

AIR-COMPRESSOR.

1,184,998.

Specification of Letters Patent. Patented May 30, 1916.

Application filed July 22, 1914. Serial No. 852,379.

To all whom it may concern:

Be it known that I, PATRICK H. REARDON, a citizen of the United States, and a resident of the city and county of San Francisco, 5 State of California, have invented certain new and useful Improvements in Air-Compressors, of which the following is a specification.

My invention relates to air compressors 10 and has for its main object to extend their usefulness.

The ordinary type of compressor now in general use employs puppet valves controlled by springs. This results in certain 15 undesirable effects. In the great majority of installations these effects are not seriously detrimental. They do, however, limit the employment of this type of device and exclude it from a large field of usefulness, for 20 which it is otherwise adapted.

So an object of the present invention, stated generally, is to provide a compressor, which, while maintaining an equally high or producing a greater efficiency than puppet 25 valve compressors, avoids the undesirable effects referred to.

An ordinary puppet valve, owing to its inherent characteristics, is sudden in its opening and non-positive in its action. The 30 necessary presence of its spring makes it especially so in closing, that is to say, it hammers and "flutters". Many attempts have been made to remedy its defects by various means, such as reducing the area of 35 its seat, adjustment of the springs, and lightening its weight. These, however, are ineffective, and particularly so when it is attempted to enlarge the effectiveness of a given compressor by increasing its speed.

40 This whole matter of compressor valves is beset by mechanical difficulties which confine to narrow limits the possibility of variations in puppet valves looking toward the elimination of their objectionable effects.

45 Hammering of the puppet valve upon its seat has heretofore necessitated a large margin of safety, and consequent weight of valve to insure a reasonable length of service, and avoid, to the greatest possible extent, that ever present source of disaster in compressors, the fracture of a valve, and the introduction of a fragment into the compressor cylinder.

50 Reduction in seat area shortens the life 55 of a valve and reducing the strength of a

controlling spring enhances the undesirable fluttering of the valve and renders it otherwise inefficient. Thus it comes about in compressors that even with the best proportions of the valve and spring, the ordinary 60 puppet type of valve is violent in its action, and exceedingly noisy.

The difference in the area of the inside and the outside of an ordinary puppet valve requires that the pressure on the smaller 65 area must be proportionally increased in order to open the valve against the lesser pressure on the opposite side. This results in a violent or popping action of the valve the instant contact of the valve with its seat 70 is broken and the larger area of the valve surface exposed to the higher pressure beneath the valve which is avoided in the type of valve herein employed to a large extent by the inherent superficial flexibility of the 75 valve. Then the peculiar characteristic of coil springs, that their resistance increases with their compression, adds another difficulty, which, with the previously described defect increases the hammering by a rebound 80 from the spring. The result of all these factors is that the stream of air under pressure is in the form of pulsations brought about by the conflict between the popping open, the momentum and the inertia of the 85 valve, and the necessarily varying resistance of its opposing spring. Owing largely to these conditions, the indicator card taken from the compressor differs characteristically from that taken from the steam engine, in that its lines are wavy through a wide range. However, aside from these undesirable effects which, as has already been intimated, do not materially affect the usefulness of compressors in a large majority 90 of employments, the ordinary puppet valve, owing to its simplicity, reliability, ease of repair and of renewal, and its instantaneous action, is exceptionally adapted to compressor use and hence it has firmly established 95 itself in the compressor art for the control of air to and from the compressor cylinder. Both of these characteristics of the ordinary compressor, its noise and the pulsatory character of the outflowing current, exclude 100 it largely from hotels, hospitals, mechanical surgery, dentistry work, and the like. In the first two possible utilities, it is unavailable owing to the noise which is conveyed through the building by the pipes. In the 110

others, owing to the effect of the pulsations on the speed of the tools employed and on the nerves of the patients.

Another object of my invention, therefore, 5 is the solution of the problem to provide a compressor of simple construction which will produce an indicator card practically free from the wavy lines characteristic of the ordinary compressor card by diminishing 10 the pulsations in the outgoing stream of air which produce them. And another object is to provide with the foregoing characteristics a compressor noiseless in its operation. And a further object is to provide a 15 compressor with the foregoing capabilities which, in addition thereto, is inherently capable of being run at a speed greater than is practicable with ordinary puppet valves.

For efficiency it is desirable that the passage 20 for the outgoing compressed air and the passage for the incoming air shall be freely open to these oppositely traveling currents to avoid "wire drawing" the air. And further, that the free opening from the cylinder 25 to the pipe line shall not be closed till all of the compressed air is forced out of the cylinder by the piston stroke. Employment of eccentrics to perform intermittent cam functions necessarily involved in timing 30 the combined inlet and outflow of air under compressor conditions is precluded by the inherent character of the motion produced by the eccentric, it being uniform, non-intermittent and sluggish, and otherwise 35 unadapted to meet the requirements of the rapid and speed varying motions required at the end of the piston stroke to properly direct the currents of air to and from the cylinder under compressor conditions. 40 This disadvantage of the eccentric is provided for in the present construction by limiting its action to the intake valve, at which point it may be advantageously employed.

45 The invention herein consists broadly in the employment of a mechanically operated valve for the intake of the air and a superficially flexible and inherently resilient metallic pressure controlled valve for the outflow of the air. These diverse forms of valves 50 and their application meet and provide for the inherent peculiarities of the action of air under the conditions at the inflow and outflow in compressors and overcome the difficulties and objections heretofore met with in compressor practice. The action of the air at the intake and outflow is wholly 55 different, and each brings about its own peculiar difficulties. As the piston starts to move to take in air, a reduction of pressure is produced in the cylinder which with the 60 puppet valve at the inlet is responded to suddenly till an approximate equalization between the inside pressure and the outside 65 atmospheric pressure is reached. In a slow

speed compressor this alternate opening and closing of the puppet valve results in a succession of valve openings and seatings, having a relation to the tension of the spring controlling the puppet valve. As the speed 70 of the compressor is increased these openings and closings develop into an impractical fluttering of the valve with its consequent rapid deterioration by hammering. Apart from this undesirable action, a point is 75 early reached at which a further increase of speed brings about no additional increase of the amount of air compressed. Furthermore, a point is soon reached in which a 80 partial vacuum is maintained in the cylinder during the whole of the intake stroke, the amount of vacuum increasing with the speed of the compressor. Thus conceivably the speed of the piston could be so great that the puppet valve spring would throw the 85 puppet valve back to its seat before more than a negligible amount of air had passed through the valve opening, and under most favorable conditions of normally high speed 90 the nature of the puppet valve brings about a destructive hammering of the valve and the fluttering rattle which precludes the employment of the compressor from some forms of service owing to its noisy character. Thus the mechanically operative 95 valve at the intake being free from all of these inherent disadvantages of the puppet valve permits of a high speed being utilized with the advantages of increasing the capacity of the compressor in proportion to 100 its speed.

The conditions met with at the outlet valve are quite different from those at the inlet valve, in that in the first place its function does not commence until the pressure 105 in the cylinder equals the pressure in the receiver and thereafter there is a mechanically superinduced continuous pressure in excess of receiver pressure. The point of commencement of the function is, of course, dependent upon the pressure in the receiver, and usually occurs at a comparatively short 110 distance from the end of the stroke. Now, while during this comparatively short distance of functional activity a puppet valve 115 will act as in the inflow, its deleterious effects cannot be so pronounced as in intake conditions. With the ordinary puppet valve 120 they are still sufficiently deleterious to render the use of the ordinary puppet valve undesirable. The necessary weight of the ordinary puppet valve to provide for sufficient strength for practical service is one of the principal elements which brings about 125 the undesired and harmful hammering and noise incident to its sudden puppet action. While with the employment of a thin flexible plate valve with its extreme lightness of weight and superficial flexibility, not only is the destructive hammer and consequent noise 130

avoided but also the puppet explosive opening is in a large measure also avoided. Thus by the combined action of these two types of valves, the mechanically operated one at the intake and the pressure actuated superficially flexible valve at the outlet, the compressor is rendered noiseless and capable of a speed of operation unavailable with the former type of puppet valve or with any other combination of valves of any kind of the same cost of construction and up-keep, and with the consequent economy due to the absence of wear and tear not possible with the ordinary puppet valve compressor.

The invention possesses other advantageous features, some of which, with the foregoing, will be set forth at length in the following description, where I shall outline in full that form of the invention which I have selected for illustration in the drawings accompanying and forming part of the present specification. In said drawings I have shown only one specific form of my generic invention, but it is to be understood that I do not limit myself to such form because my invention may be embodied in a multiplicity of forms, each being a species of my said invention. It is also to be understood that by the claim succeeding the description of my invention, I desire to cover the invention in whatever form it may be embodied.

Referring to the accompanying drawings: Figure 1 is an elevation of the compressor of my invention, showing the inlet valve actuating means. Fig. 2 is a horizontal section through the cylinder head, showing the valve arrangement. Fig. 3 is a vertical section of the cylinder head taken on the line A—A Fig. 2.

The compressor comprises a base 2 in which is journaled the crank shaft 3, which is driven by power applied to the wheel 4. Secured to the base 2 is the cylinder 5, containing the usual piston which is driven from the crank shaft 3 by suitable connecting rod. At the upper end of the cylinder is arranged the cylinder head 6 in which are arranged the inlet and outlet valves.

Formed in the cylinder head is the seat 7 in which the mechanically operated inlet valve 8 is disposed. The seat is provided with a port 9 which establishes communication between the air inlet 12 and the interior of the seat and with a port 13 which establishes communication between the cylinder 5 and the interior of the seat. The valve 8 is of the mechanically operated, oscillating type and is adapted to cut off and establish communication between the cylinder and the inlet. The valve 8 is light in weight and small in size relatively to the size of the cylinder and is oscillated by means of the lever 14, which is connected to the eccentric strap 15 surrounding the eccen-

tric 16 on the crank shaft 3 by the connecting rod 20 so that the valve moves in synchronism with the piston. Due to the lightness and small size of the valve and its small arc of movement, it is possible to greatly increase the capacity of the compressor by operating it at high speeds, which high speed is obtained without producing any vibration.

On account of the characteristics of compressors, that is, that air is drawn into the cylinder during substantially the whole of the suction stroke and expelled during only a portion of the compression stroke, the eccentric, with its inherent sluggish motion, is adapted for the control of the inlet valve, but is inefficient when applied to the outlet valve. The mechanically operated type of valve is more efficient at the inlet than the puppet type of valve, because it permits a steady and continuous inflow of air during the suction stroke and is not subject to the deleterious flutterings of the ordinary puppet valve.

The characteristics of compressors are such that it is advantageous to employ a pressure controlled valve at the outlet or discharge, but the inherent disadvantages of the ordinary puppet valve are such that the use of the ordinary puppet valve precludes the use of the compressor from many forms of service and prevents the compressor from being operated at a high speed. To overcome these and other inherent disadvantages of the ordinary pressure controlled valve, I have employed a valve of the puppet or pressure operated type which has all of the advantages of the ordinary puppet valve, where its advantages are highest, without any of its disadvantages.

The outlet valve of the present invention comprises a thin metallic plate 17 superficially flexible and inherently resilient. The plate 17 is preferably formed in the shape of a disk and has an imperforate peripheral portion 18 which seats on the annular discharge port 19 formed in the bottom wall 21 of the cylinder head. The discharge port is formed of a plurality of concentric segmental passages, the ribs between the passages serving to support the central core 22 to which the valve 17 is attached at its center. The valve is provided with one or more preferably concentric slots or slits 23—24 to provide for the necessary superficial flexibility and the concentric slots or slits are preferably joined by slots or slits 25, whereby the flexibility is increased. The valve is formed of resilient metal, such as steel, and possesses inherent resiliency so that the use of a spring to seat the valve is obviated, thereby producing a structure which not only possesses material advantages of operation over the ordinary puppet valve, but is cheaper in construction.

The present valve seats and unseats with a rolling motion, another feature which distinguishes it from the ordinary puppet valve, and its consequent blow. The disk 5 flexes upwardly in a curve, the periphery thereof preceding the portion which lies within the periphery. Means are also provided for limiting the unseating movement of the valve, so that it may not be subjected 10 to undue strains. Overlying the valve and in contact therewith at the center is a backing plate 26 having a convex lower surface against which the valve is moved when unseated, the curvature of the backing plate 15 being sufficient to allow the periphery of the valve to move away from its seat the necessary distance to permit the free passage of the compressed air. The backing plate which also holds the center of the 20 valve in place is secured to the central core 22 by a cap screw 27. Access to the disk valve is obtained through the normally plugged tapped hole 28 formed in the top wall of the cylinder head. The compressed 25 air passes from the cylinder to the valve chamber 29 in the cylinder head, whence it discharges through the outlet port 31.

In the construction shown in Fig. 2 I have employed two discharge valves and

the backing plate of one of the valves has 30 been removed to disclose the construction of the valve.

By employing a mechanically operated valve at the inlet and a superficially flexible metallic valve at the outlet, I have provided 35 a compressor which is not only noiseless in operation, but which is efficiently operated at high speeds, thereby permitting a small compressor operated at high speed to have the same capacity as a large compressor of 40 the ordinary type driven at standard speeds.

I claim:

A compressor comprising a stationary cylinder, a piston movable therein, a driven crank shaft to operate the piston, an air inlet of relatively small size with respect to the area of the cylinder, a mechanically operated rotary valve controlling the air inlet, an outlet for the compressed air and a flexible metallic pressure operated valve controlling the outlet. 45

In testimony whereof, I have hereunto set my hand at San Francisco, California, this 16th day of July 1914.

PATRICK H. REARDON.
